BASKETBALL GAME BOARD APPARATUS

Nicholas D. Trbovich, West Seneca, and Eugene R. Trunzo, North Tonawanda, N.Y.; said Trunzo assignor to Servotronics, Inc., Buffalo, N.Y.

Filed Sept. 27, 1971, Ser. No. 184,325

Term of patent 14 years

Int. Cl. D21—01

U.S. Cl. D34—5 SS

Fig. 1.

FIG. 1 is a top plan view of a basketball game board apparatus, showing our new design;

FIG. 2 is a view of one side thereof in elevation, the opposite side being identical to the side shown; and

FIG. 3 is a view of one end thereof in elevation, the opposite end being identical to the end shown.

We claim:

The ornamental design for a basketball game board apparatus, substantially as shown and described.
